UNITED STATES PATENT OFFICE

BURDETT B. BRIGGS, OF CHICAGO, ILLINOIS

CARBURETOR

Application filed July 20, 1928. Serial No. 123,741.

This invention relates to carburetors for internal combustion engines and forms a continuation in part of my prior application filed March 13, 1926, Serial Number 94,549.

More particularly the invention relates to the fuel bowl or reservoir of such a carburetor.

One important object of the invention is to provide an improved arrangement whereby the fuel in the lower part of the carburetor is well heated previous to its entering the nozzle in the mixing chamber of such carburetor thus permitting the use of a low grade of liquid fuel.

15 A second important object of the invention is to provide an improved form of such a carburetor wherein the liquid hydrocarbon fuel is maintained at an even temperature while running.

20 A third important object of the invention is to provide improved adjustable means for governing the temperature of the fuel, the carburetor being also provided with indicating means for the temperature whereby the correct adjustment of the temperature governing means may be obtained.

A fourth important object of the invention is to provide an improved and novel form of bowl and arrangement of air intake therein.

25 30 A fifth important object of the invention is to provide an improved arrangement of fuel controlling float in such a carburetor.

A sixth important object of the invention is to provide improved means for holding the 35 fuel bowl and the air inlet and mixing chamber assembled.

With the above and other objects in view as will be hereinafter apparent, the invention 40 consists in general of certain novel details of construction and combinations of parts hereinafter fully described, illustrated in the accompanying drawings and specifically claimed.

45 In the accompanying drawings like characters of reference indicate like parts in the several views, and:

Figure 1 is a side elevation of the improved carburetor applied to an engine, the view being partly in section to show certain features.

Figure 2 is an enlarged end elevation of the carburetor removed from the engine.

Figure 3 is an enlarged detail section on the line 3-3 of Figure 1.

Figure 4 is a section on the line 4-4 of Figure 2.

Figure 5 is a section on the line 5-5 of Figure 2.

Figure 6 is a detail view, partly in section, showing the arrangement of the two piece top or cover for the bowl.

The carburetor as constructed in accordance with this invention is provided with a bowl or fuel reservoir having a bottom 10 and side wall 11. This bowl is of elongated form having parallel side walls and semi-circular end walls. Beneath the bottom 10 in spaced relation thereto is a hot gas jacket bottom 12 which extends at its periphery beyond the bottom of the bowl and carries an upstanding side wall 13 connected to the side wall of the bowl at its top by a top wall 14. Thus beneath the bottom and around the lower part of the bowl extends a hot gas jacket which is high enough to at least reach the normal fuel level in the bowl. Between the bottoms 10 and 12 there is formed a longitudinally extending baffle rib 15 which runs from one end wall of the bowl towards the other and terminates short of the end portion of the wall 13. This baffle rib has a laterally enlarged portion 16 positioned centrally of the bowl so that a suitable opening may be formed therein for the reception of a tube having a vertical portion 17 provided with a threaded lower end, and a horizontal portion 18 having a securing flange 19 at its extremity by means of which it may be secured to the engine E in the usual manner. Just above the threaded end the tube is provided with an annular flange 20 which seats in a suitable rabbet formed in the bowl bottom and on this threaded end is screwed a sleeve nut 21 which thus secures the tube and bowl firmly together. Extending radially inward from the side of the tube 17 at a point just above the bottom of the bowl is a small tube 22 which has its terminal portion 23 turned upwardly in the axis of the tube 17. The opening in the upper end of 100

this tube 23 is controlled by a needle valve 24 having a threaded portion 25 on its stem which is screwed through a suitable threaded opening in the bend between the portions 17 and 18 of the air tube. A knurled head enables this valve to be adjusted as desired. A vent 26 leads from the upper part of the bowl to the upper part of tube 17. As thus constructed the lower part of tube 17 constitutes an air intake while the upper part forms a mixing chamber.

The cover for the bowl consists of two similar halves 27 meeting in a straight line which passes through the axis of the tube 17. 15 Each of these halves has a rounded end which is secured to the wall 11 by a screw 28 and other screws 29 pass through notches in the coacting edges of the cover so that the heads of these screws 29 bear equally on both halves of the top or cover and hold them in place. On one of these heads is an externally threaded nipple 30 for connection to a fuel supply pipe 31 receiving fuel from a suitable source of supply (not shown). The 20 lower end of the nipple 30 has its opening controlled by a needle valve 32 the stem of which is slidably supported by yokes 33 secured to the bowl bottom 10 and to the underside of the top half 27. On this stem is 25 fixed a float 34 so positioned that as soon as the fuel rises in the bowl to the proper level the float will act to seat the needle valve 32 and thereby prevent further entry of fuel until a portion of that in the bowl has been 30 drawn off.

It will be noted that this arrangement provides for a direct lift of the needle valve and dispenses with the use of toggles or levers.

The other half of the top is provided with 40 a depending internally threaded nipple 35 wherein is screwed the threaded portion of a thermostat having a bulb 36 extending downwardly below the fuel level of the bowl and provided on its upper and outer end with an 45 expansion element 37 here shown as a single expansion cell though it is obvious that there may be as many of these cells as are necessary to effect proper working of the device.

On one side of the carburetor is a nipple 38 50 for the admission of hot gases while a similar nipple 39 on the other side provides an exhaust for such gases. Hot gas is preferably supplied to the nipple through a tube 40 which penetrates the wall of the engine exhaust pipe 41 and has its end beveled to face the flow of the gases of combustion passing from the engine. Similarly the exhaust from the nipple 39 is carried by a tube 42 back to the pipe 41, this tube 42 having a beveled 55 end facing away from the gas flow through said exhaust pipe. Screwed into a horizontal wall of the bowl is a thermometer casing 44 containing a thermometer 45 the mercury of which may be observed through a window 46 60 in the part of the casing which extends above

the wall 43. The thermometer casing is provided with a cap carrying a bracket 47 whereby to a lever 48 is pivoted intermediate its ends. One arm of this lever is pivoted to a bracket 49 carried by the cell 37 while the other arm has the threaded upper end of a link 50 passing in a substantially vertical direction therethrough. The lower end of this link is pivoted to the end of a valve lever 51 fixed to the stem of a butterfly valve 52 located in the nipple 38. A spring 53 urges this arm 51 to raised position and a nut 54 threaded on the link 50 below the lever 48 limits the lift of this arm with respect to the lever and consequently controls the opening of the valve 52. 80 As the heat of the fuel in the bowl rises the cell 37 expands and the valve 52 is moved toward closed position and thus the hot gases are restricted in their flow around the bowl. Conversely if the fuel cools, the valve will be 85 opened wider. Thus the fuel is kept at a nearly uniform temperature while the engine is running. The degree of this temperature may be controlled by adjustment of the nut 54. 90

A drain cock 55 is provided for the bowl and a throttle valve 56 is provided to control the flow of carburized air through the tube or pipe 18.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a carburetor, a bowl having a top and a bottom, a nipple adapted for connection to a source of fuel supply carried by the bowl top, vertically aligned yokes supported within the bowl at the top and bottom thereof, an open full gap between the top of the lower yoke and the bottom of said bowl, a needle valve supported in said yokes for vertical sliding movement and positioned to close the nipple opening when raised, and a float carried by said valve.

2. In a carburetor, a liquid fuel bowl, a chamber for hot gases around said bowl, gas supply and exhaust nipples communicating with said chamber, a valve for controlling the flow of gas into the chamber, a thermostat having a bulb within the bowl and an expansion cell at its upper end, a bracket supported from said bowl, a lever pivoted between its ends on said bracket and having one end carried by said cell, a valve lever fixed to the valve, a link fixed to the end of the valve lever and extending through the re- 130

maining end of the first mentioned lever, an adjusting nut threaded on said link and bearing against the under side of said first lever, and a spring connected to said valve lever 5 and urging the valve to open position.

3. In a carburetor, a bowl, a chamber for hot gases around said bowl, gas supply and exhaust nipples communicating with said chamber, a valve for controlling the flow of 10 gas through the supply nipple, a thermostat having a bulb within the bowl and an expansion cell at its upper end, a bracket supported from said bowl, a lever pivoted between its ends on said bracket and having one end 15 carried by said cell, a valve lever fixed to the valve, a link connecting said levers, and means to adjust the effective length of said link.

4. In a carburetor having a liquid fuel reservoir, a chamber on the under side of said 20 reservoir, an inlet port and an outlet port communicating with said chamber at one side thereof, a rib in the chamber having one end in engagement with the side of said chamber between said ports and the opposite end 25 spaced from the opposite side of said chamber for directing heat therein from the inlet to outlet port, said rib extending from a point on the wall of said chamber between said inlet and outlet to a point adjacent to the opposite wall of said chamber, and means connected with the inlet port to supply heat to 30 said chamber, for the purpose set forth.

5. In a carburetor, a liquid fuel bowl, means for heating the fuel in said bowl, a 35 thermostatic device controlled by the temperature of the fuel in said bowl, means actuated by said thermostatic device for controlling said heating means, an adjustable connection between said device and said 40 second mentioned means and temperature indicator visible externally of said carburetor showing the temperature of the fuel in said bowl.

6. In a carburetor, a liquid fuel bowl, a 45 heating chamber about said bowl, a tube for conveying a heated fluid to said chamber, a thermostatic device controlled by the temperature of the fuel in said bowl, a shut-off in said tube, a connection whereby said device actuates said shut-off, adjusting means in 50 said connection for determining the degree of actuation of said shut-off and a temperature indicator visible externally of the carburetor showing the temperature of the fuel in said bowl.

In testimony whereof I affix my signature.
BURDETT B. BRIGGS.
